(57) **CLAIM**

The ornamental design for a container for food packing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a container for food packing of the present invention.

FIG. 2 is a front elevational view of the container for food packing of FIG. 1.

FIG. 3 is a rear elevational view of the container for food packing of FIG. 1.

FIG. 4 is a left side elevational view of the container for food packing of FIG. 1.

FIG. 5 is a right side elevational view of the container for food packing of FIG. 1.

FIG. 6 is a top plan view of the container for food packing of FIG. 1; and,

FIG. 7 is a bottom plan view of the container for food packing of FIG. 1.
